UNITED STATES PATENT OFFICE

144,150

DESIGN FOR A WHEELED LADDER TOY

Richard Appel, Kew Gardens, N. Y.

Application May 1, 1945, Serial No. 119,335

Term of patent 7 years

(Cl. D34—15)

To all whom it may concern:

Be it known that I, Richard Appel, a citizen of the United States, residing at Kew Gardens, Long Island, county of Queens, State of New York, have invented a new, original, and ornamental Design for a Wheeled Ladder Toy, of which the following is a specification, reference being had to the accompanying drawing, forming part thereof.

ladder toy with the ladder in erected position, showing my new design;

Fig. 2 is a top plan view on a reduced scale of the wheeled ladder toy shown in Fig. 1, with the ladder removed.

I claim:

The new ornamental design for a wheeled ladder toy, as shown and described.

RICHARD APPEL.
